UNITED STATES PATENT OFFICE.

WILLIAM F. SOETY, OF ERIE, PENNSYLVANIA.

FOLDING CARPENTER'S AND JOINER'S JACK.

SPECIFICATION forming part of Letters Patent No. 741,562, dated October 13, 1903.

Application filed February 10, 1903. Serial No. 142,793. (No model.)

To all whom it may concern:

Be it known that I, WILLIAM F. SOETY, a citizen of the United States, residing at Erie, in the county of Erie and State of Pennsylvania, have invented certain new and useful Improvements in Folding Carpenters' and Joiners' Jacks; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to improvements in folding carpenters' and joiners' jacks, and has for its object the production of a folding portable jack mechanism adapted to support a door or window in an upright position while 20 the same is being fitted and when not in use to be folded up, so as to occupy but little space.

The features of my invention are herein-after fully set forth, and illustrated in the 25 accompanying drawings, in which—

Figure 1 is a side elevation, in slight perspective, of my improved folding jack, showing in dotted lines a door secured therein. Fig. 2 is a top or plan view of the same. Fig. 30 3 is a view in elevation of one section of the same.

In the construction of my invention I provide an upright post A, which is bifurcated at its lower end, so as to form feet a a. To 35 sustain the post A in an upright position when in use, I pivot legs B B to the upper part thereof by means of a bolt and thumb-nut a', which legs when in use are secured in an inclined position by hinged braces b b 40 and b', secured at one end by eyebolts and at the other end by hooks thereon engaging eyes on the upright A and one of the legs B.

Upon the upright A, I place clamping-jaws C C', which are adjustable thereon and are 45 secured thereto by means of thumb-screws c c. The lower clamp C' is provided with a web or plate c' across its lower face, upon which the end of a door or sash secured therein can rest. Both the upper and lower clamp- 50 ing-jaws are fitted with clamp-screws D, having on their inner ends face-plates d to prevent marring the surface of the wood clamped

therein and on their outer ends hand-wheels d' for operating the same; but they may be operated in any other convenient manner. 55

For supporting the opposite end of the door or sash in a level position when the same is secured in the clamps C C', I provide an upright post E, the lower end of which is bifurcated, so as to form feet e e. This upright E 60 is further sustained in an upright position by means of an inclined leg or brace F, removably secured to the upright by means of a sleeve F' and thumb-screw f. Upon the upright E, I place a U-shaped clamp G, which 65 is provided with a clamping-screw D', hand-wheel d', and plate d'', like the jaws C and C', and adapted to support and clamp the lower edge of a door or sash placed therein. This clamp G can be adjusted vertically, as 70 required, by means of the thumb-screw g. (See Fig. 1.)

In the construction of this jack I preferably make the lower ends of the legs or feet a a, B B, and e e somewhat sharpened, so that 75 the same will not slip easily upon a floor when it is necessary to plane the edge of a door or sash supported in the jack.

In operation the jack-sections are placed upon the floor with the legs B B and F in a 80 bracing position, as shown in the drawings, and the braces b b and b' hooked securely in the eyebolts thereon. The lower clamps C' and G are then adjusted upon the uprights A and E at the elevation desired. The door 85 or sash to be fitted is then placed thereon between the clamping-plates d and d'' and the jaws of the clamps C' and G. The upper portion of one end of the door or sash is also secured in the clamp C. The clamping-screws 90 D D and D' are then turned until the door or sash is securely fastened in both sections of the jack. When the jack is not in use, the parts thereof can be folded together in such a compact shape as to be conveniently portable. 95

Having thus fully described my invention, so as to enable others to construct and utilize the same, what I claim as new, and desire to secure by Letters Patent of the United States, 100 is—

The combination in a folding carpenter's jack of an upright having its lower end bifurcated and inclined outward, brace-legs piv-

otally secured to the upper part of said upright, detachable braces between the lower parts of the legs, and between the legs and the upright, screw-adjusted clamping-jaws 5 mounted upon the upper and lower portions of said upright, both of which clamping-jaw mechanisms are also vertically adjustable thereon, whereby a door or sash of any size

can be secured and firmly held thereby substantially as set forth. 10

In testimony whereof I affix my signature in presence of two witnesses.

WILLIAM F. SOETY.
